6 Claims. (Cl. 98—40)

2

with the removable and replaceable core. This damper, when in position, will enable control of the total flow of air supplied to the diffuser by means of a readily accessible screw adjustment on the accessible exterior face of the diffuser combination.

With the foregoing and other objects in view, the invention consists of the novel construction, combination and arrangement of parts as hereinafter more specifically described, and illustrated in the accompanying drawings, 10 wherein is shown an embodiment of the invention, but it is to be understood that changes, variations and modifications can be resorted to which fall within the scope of the claims hereunto appended.

In the drawings wherein like reference characters de-

15 note corresponding parts throughout the several views:

Figure 1 is a face plan view of the diffuser with the removable and adjustable core in position therein, showing the form for achieving a two-way air flow construction;

20 Fig. 2 is a fragmentary side elevational view partly in section showing the interior construction;

Fig. 3 is a transverse vertical sectional view upon the line 3—3 of Fig. 1;

25 Fig. 4 is a horizontal transverse sectional view upon the line 4—4 of Fig. 3;

Fig. 5 is a transverse horizontal sectional view upon the line 5—5 of Fig. 3;

Fig. 6 is a transverse vertical sectional view upon the line 6—6 of Fig. 5;

30 Fig. 7 is a transverse sectional view similar to Fig. 6 showing an alternative extreme limiting position of the adjustable vanes;

Fig. 8 is a fragmentary transverse sectional view upon the line 8—8 of Fig. 3; and

35 Fig. 9 is a perspective view showing one of the standard spacer and air channel partition members with the attachment flange and tab.

Referring to Figures 1, 2 and 3, there is shown an air diffuser A having an outer frame structure B which 40 extends into the ceiling with a face structure C. The removable core D is held in position by means of the connections E and F. Positioned on the removable and replaceable diffuser construction is the adjustable damper construction G which has an exteriorly adjustable connection H.

The basic vanes J, one of which is shown by itself in Fig. 9, assure a correct positioning and location of the main deflector and channel members K.

Referring specifically to Figure 9, the standard air 50 channel divider and locating elements J have trapezoidal shapes 10 with an oblique edge 11, a straight right angle edge 12, a short end edge 13 and a long end edge 14. The straight edge 12 is provided with an integral attachment tab 15 having oblique cutoff portions 16 and 17 55 which is designed to be spot welded at two points 18 and 19 to the underside 20 (see Fig. 4) of the outwardly extending deflector portion 21 of the channel member K.

The tab 22 extends in the opposite direction from the tab 15 and from the edge 14 of the unit J from a corner 60 23. This tab 22 will be attached to the next deflector channel K and to the inside straight flange 24 thereof (see also Fig. 4).

These tabs 22, together with the tabs 15, will correctly locate and space the channels K in the removable 65 deflector core D.

As seen in Figure 6, these tabs are usually spot welded at one point 25 to the straight flange portions 24 of the deflector members K. It will be noted that the entire interior of the core is made up of the channel members 70 K and the location units J and these will be assembled inside of an exterior sleeve 26 and an outwardly directed oblique flange 27. The flange 27 has a socket 28, as

The present invention relates to diffuser constructions and it particularly relates to devices for distributing air for ventilating and air conditioning purposes into a room or enclosure.

It is among the objects of the present invention to provide a novel, simple, readily assembled, durable air diffuser construction in which the louvers, vanes and channels may be readily assembled by relatively low cost mass production methods and a minimum of labor costs.

Another object is to provide a simple, readily installed replaceable air diffuser construction in which the interior construction may be readily removed and in which the air streams may be adjustably controlled from the exterior of the diffuser construction.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the above objects, it has been found most satisfactory to provide an exterior frame structure which may be readily mounted into a ceiling and which is provided with a lower receptacle portion to receive the air diffuser construction and an upper receptacle portion in which there is provided a controllable damper or vane construction adjustable from the exterior of the device.

It is a particular feature of the present invention that the core may be readily removed and that the damper or adjustable vane may be removed with the core and different types of diffuser cores may be inserted to give control for one-way, two-way, three-way or four-way air distribution. It is another particular feature of the present invention that the diffuser core itself is assembled by channel members each having interior parallel elements with exterior obliquely directed deflector members for controlling and deflecting the air flow.

An important feature of the present invention resides in the fact that the correct spacing and location is achieved by a standard construction of vane elements of trapezoidal shape for separating the streams of air, which trapezoidal vanes have integral flaps along one long edge of the trapezoid for welding to one side of the structure and a tab from an opposite short side which is welded to a different side.

As a result there is obtained a controlled location and spacing of the channel and deflector members. Furthermore, this will enable a ready assembly of the entire diffuser construction with relatively few standard shaped parts and with the use of standard jigs and form elements.

Separable external frame and interior core enables replacement of the core so as to give one-way, two-way, three-way or four-way air distribution as may be desired.

Desirably, there is assembled with the removable core a damper construction which is adjustable from the lower exterior of the diffuser which may be removed

shown in Fig. 3, which receives a filister head 29 forming part of the attachment E.

The filister head 29 has a shaft 30 with a cross bar 31 which cams against the structure 32 to hold the core tightly in position. The structure 32 is held in position by the flange 33 and the spot welds 34, as shown in Fig. 2.

The other side of the core is detachably secured by the tongue 35 forming part of the attachment structure F.

The tongue 35 is designed to be inserted into the slot 36 in the conforming oblique peripheral flange 38 of the exterior frame structure B. The flange 38 then extends into the flat encircling face plate 39 forming part of the major structure C which terminates in the upwardly directed flange 40 which receives the gasket 41.

The tongue 35 is offset from the base structure 42 (see Fig. 8) which is spot welded to the peripheral flange 27 of the core D.

Assembled to the removable core D will be the damper structure 61 which will be located by means of the tab members 60 (see Figs. 2 and 3). These tab members 60 will have flanges 61 mounted upon the inside or lower face of the damper and will have the depending tongue 62 which fits in the recess 63 between the collar 26 and the frame structure B (see particularly Fig. 2). The damper structure, itself, which is best shown in Figs. 2, 3, 5, 6 and 7, consists of the exterior rectangular frame structure 64 having the opposite side walls 65 and the intervening walls 66 and 67 which carry the pivot connections 68 and 69, respectively.

The pivot connections 68 and 69 will carry the swinging members 70 having the oblique edge portions 71. When the members are closed these oblique edge portions will contact at 72 and abut each other (see Fig. 7). When they are open, as shown in Figs. 2 and 6, they will be parallel to each other. These vanes are actuated from open to closed position or to intermediate positions by means of the actuator H which has a straight projecting portion 73 and an oblique extension 74 to extend into the space 75 (see Fig. 3).

The space 75 will be readily accessible from the outside of the diffuser and will permit the element 70 to be changed from the position as shown in Fig. 6 to the position as shown in Fig. 7.

The handle or adjusting element H has an innermost end 76 which is spot welded to the connector element 77 (see Fig. 3). The connector element 77 when moved by the handle H will act upon the crank pins or studs 78 which fit in the slots 79 in the end flanges 80 of the swinging damper members 70. It will be noted that whereas one damper element 70 turns in one direction another will turn in an opposite direction from the position in Fig. 6 to the position in Fig. 7. The adjustable damper structure G may be removed from the detachable core D where full flow of air through the throat B is desired. Where it is desired to control the flow of air, the damper is inserted and the damper elements 70 are adjusted to a position varying from the position shown in Fig. 6, which is a full flow position, to the position shown in Fig. 7 in which the air is substantially closed off. It will be noted that as the lever H is moved backwardly and forwardly, as indicated by the double arrow 81 in Figures 6 and 7, the pivot pin 69 will be moved from one end to the other end of the slots 82 in the structure 77. This will cause the semi-circular end flanges 80 to swing from the position of Fig. 6 to the position of Fig. 7 or vice versa, moving the studs 78 and alternately varying the position of the damper element 70. When this occurs, the studs 78 will move to the opposite end of the slots 79.

The lower throat section 90 of the frame B will enclose the throat 26 of the detachable core D while the upper throat section 91 will enclose the damper structure G.

The outer housing consists of the transverse or ver-

tical inlet conduit B and the outwardly flaring side walls 38 which connect to the outside flush flange C which forms a frame encircling the outlet of the air diffuser and contacting and pressed against the periphery of the opening in the ceiling.

The inside housing includes the conforming parallel enclosure 26 which fits in the outlet end of the transverse conduit B and conforms in size and cross section thereto.

Connected to the outer end of the enclosure 26 are the oblique outwardly flaring members 27 which form a flaring throat portion of the inner housing of the core which conforms in shape, cross section and size to the outwardly divergent flaring plates 38 of the outer housing.

15 The vanes or louvers J and the oblique deflector members or louvers K extend from interior side to interior side of the housing of the removable core and they terminate flush with the ceiling line or with the plane of the frame C as indicated in Fig. 3.

20 In operation, the assembly is made on jigs with oblique deflector structures K being assembled to each other and being correctly spaced and positioned by means of the trapezoidal elements J which are spot welded in position at 18 and 19, as shown in Fig. 4, and at 25 as shown in 25 Fig. 6. These cores may be changed to give one-way, two-way, three-way or four-way air distribution. They are readily removed and inserted in position by turning the screw element 29 one-quarter of a turn and unhooking the hook 35 from the slot 36. The damper G will 30 usually come out with the diffuser.

To adjust the damper the lever H is readily accessible in the space 75 and may be used to correct the position of the damper elements 70.

While there has been herein described a preferred 35 form of the invention, it should be understood that the same may be altered in details and in relative arrangement of parts within the scope of the appended claims.

The oblique louvers or plates K extend from side to 40 side of the conical or pyramidal section 27 and they have an oblique portion 21 to which the flange 15 of the element J is spot welded and they have a section 24 parallel to the throat to which the end tab 22 is spot welded.

It will be noted that the tab 22 as shown in Fig. 4 extends in an opposite direction from the flange 15.

45 The ends of the members K are mounted upon the oblique sides 27 of the throat.

The upper flange portion 24 of each of the oblique vanes or louvers K extends parallel to the axis of the 50 throat or conduit B and serves as a means of a connection of the tabs 22.

The ends of the vanes are also attached to the terminal portion 26 of the oblique member 27 and the vanes therefore not only are spaced apart by the elements J but are also secured to the vertical flange 26 as well as 55 the oblique flange 27 of the removable core D.

In respect to Fig. 4, the throat section is indicated by B and the divergent or oblique portions have not been shown.

Having now particularly described and ascertained 60 the nature of the invention, and in what manner the same is to be performed, what is claimed is:

1. A rectangular air diffuser construction fitted into a recess in a ceiling having an interior straight transverse throat section connected to an interior conduit system, 65 an outwardly directed flaring throat section at the ceiling with outwardly diverging oblique sides and a terminal outwardly extending flange having peripheral ceiling means flush with the ceiling, a removable core having an outer flaring throat portion conforming to and jammed against said flaring section and having a straight transverse portion extending inwardly from said outer flaring portion into the transverse throat section and a plurality of spaced oblique louvers extending across said flaring portion from side to side thereof, a plurality of obliquely 70 positioned spacing and locating elements extending be- 75

tween and mounted upon said adjacent louvers and terminal detachable side connections between the adjacent oblique sides of the flaring section and portion to jam said flaring section and portion together.

2. The construction of claim 1, said oblique louvers having inwardly directed transverse portions extending parallelly to the straight transverse portions and said elements being at one side mounted thereon and at the other side being mounted upon the oblique louvers.

3. The construction of claim 1, said elements consisting of trapezoidal base portions with outwardly and oppositely directed flanges from adjacent edges of said portion mounted upon adjacent louvers.

4. The construction of claim 1, said detachable side connections consisting of a slot and tongue connection at one side and a pin and double inclined flange cam arrangement at the other side.

5. A ceiling air diffuser of the type recessed into an opening in the ceiling having its outlet side flush with ceiling and having an inside transverse connection inside of the ceiling to receive incoming air from an interior conduit system, said diffuser having an outer frame structure, a peripheral frame having a central opening surrounding and extending outwardly from said frame structure, and having an inside sleeve smaller in cross sectional area than said central opening and terminating inside of and substantially spaced inwardly of said peripheral frame to form an inlet conduit, an outwardly diverging flaring throat section attached at its inner narrow end to the outer end of the inlet conduit and at its

25
30

outer end to the central opening of the frame structure, and a removable core having an interior straight encircling wall section projecting into and conforming in shape and cross section to the transverse inlet conduit, said core being fitted into and held with said frame structure and having an outwardly flaring portion attached to and extending outwardly from the interior wall section and conforming in shape and substantially in cross section to the flaring throat section, transverse diffusing vanes extending from interior side to interior side of the wall section and from interior side to interior side of the flaring portion of the core to direct air flowing through the core and cooperating means at opposite sides of the core and outer housing to hold said core detachably in said frame structure, said diffusing vanes being separated and held in spaced relationship to one another by trapezoidal plates extending therebetween and having end tabs welded thereto.

6. The diffuser of claim 5, said cooperating means consists of a screw connection at one side and a slotted tongue connection at the other side.
